UNITED STATES PATENT OFFICE.

MIKE CHERZASTEK, OF PASSAIC, NEW JERSEY.

CABBAGE-SLICER.

1,398,257.

Specification of Letters Patent. Patented Nov. 29, 1921.

Application filed April 7, 1920. Serial No. 371,344.

To all whom it may concern:

Be it known that I, MIKE CHERZASTEK, a citizen of Poland, residing at Passaic, county of Passaic and State of New Jersey, have invented certain new and useful Improvements in Cabbage-Slicers, of which the following is a specification.

This invention relates to improvements in vegetable cutters, particularly cabbage slicers, and it is the object of my invention to produce a device adapted to facilitate the operation of slicing with economy and despatch.

A further object of my invention is to provide a device of this character that will combine simplicity and economy in construction with durability and efficiency in use.

My invention consists in a table having a top hinged thereto and a horizontal disposed rotary cutting or slicing disk below the top made of spring metal and so constructed as to adapt it to be adjusted to regulate the depth of the slice.

My invention further consists in the combination, with a suitable driving gearing and rotary cutter, of a cover or top having a pocket therein for the purpose of holding the articles being cut, and other pockets below the rotary cutter for the removal of the slices.

My invention further consists in the parts and combination of parts as will be more fully described and pointed out in the claim.

My improvement will be readily understood from the following description, taken in connection with the accompanying drawings, in which—

Figure 1 is a front view of a device embodying the cabbage slicer constructed according to the present invention.

Fig. 2 is a top plan view of the device with the hinged top raised.

Fig. 3 is a top plan view of the table used in connection with my improved slicer.

Fig. 4 is a top plan view of the gearing and coöperating parts after removal of the table top and the cutting disk.

Fig. 5 shows in detail views the construction of the rotary cutter and one of its blades.

Figs. 6 and 7 are detail views showing the blade construction.

Referring to the drawings, 10 indicates a table of the ordinary well known con-

struction having 4 legs 11, side strips 12 and a top 13 hinged to the rear strip 12 as at 14 and adapted to be kept in its lowered normal position by hooks 15 secured to its underside near the front edge thereof and engaging eyes 16 secured to strip 12.

Over a substantially square opening in the flat top 13 near one end thereof, a box 17 is secured and kept in position by a holding cleat 18 or the like.

Pivots secured to the inner wall of one of the end strips 19 of the table frame is an arm 20 the free end of which is pivotally secured to the free end of another arm 21 pivotally secured at its opposite end to a cleat 22 on the underside of the table plate.

To the lower edges of the front and rear strip 12 a transverse bar 23 is fastened to which is secured a bracket 24 having a longitudinal slot 25 in which a bevel gear 26 is working which is rotating with a horizontal shaft 27 journaled in suitable bearings secured to the lower edges of strips 12 and downwardly directed projections of the bracket 24. A crank handle 28 projecting laterally from the table is adapted to be manually operated for rotating the shaft 27 and gear wheel 26.

A vertical shaft 29 is rotatably secured in the bracket 24 and carries somewhat above the same a bevel gear 30 in mesh with the gear 26. The gear 30 receives its rotation from the gear 26 upon the operation of handle 28 and transmits the same to shaft 29, the upper end of which works in a suitable bearing 31 formed in a metal plate secured to the underside of the table top.

At a small distance below said bearing 31 the vertical shaft 29 is squared to provide a seat for a cutter disk 32, which is pressed against its seat by a nut securing said disk to the shaft so that it participates in its rotation.

The disk 32 is composed of wings 33 having a configuration illustrated in detail in Fig. 5, and having substantially knife shaped edges curved on the arc of a circle, the outer edges of two adjoining disks being connected by bands 34, the ends of which are secured to inner faces of two adjoining bands near the periphery of the disk by means of adjusting screws and nuts.

The inner ends of the peculiarly shaped wings 33 are secured to a spider-like holder 35, the single wings of which have beveled

edges. This holder 35 and its wings are secured to the underside of the single wings 33 by means of screws and nuts allowing of a limited adjustment while in its center the 5 spider has a square hole allowing a securing of the disk to the vertical shaft.

It will be clear that by suitable adjustment of the wings in their relative position by means of the screws and nuts the distance 10 between the adjoining cutting edges of two disks may be varied at will and thus thicker or thinner slices may be cut from a head of cabbage upon the operation of the handle and slicing disk through the intermediary of the 15 shafts and gears.

At the end of the bracket 24 a rhomboid shaped box 36 is provided below the cutter disk open on top and bottom through which the cut off cabbage slices fall into a suitable 20 receptacle placed therebelow, and a small board 37 is placed between the outer wall of said box and the end strip 19 of the table to hold said box 36 in place.

The operation of my device is as follows— 25 A head of cabbage to be sliced is placed in the container 17 after the table top 13 has been secured to the side strip 12 by means of the hooks and eyes 15 and 16 and pressed down into said box by the left hand, while 30 the crank 28 is turned with the right hand, the table being of such a height that the knee of the operator may rest upon the top 23.

The turning of the crank will operate through the intermediary of the horizontal 35 shaft 23, the bevel gears 26 and 30 and the vertical shaft 29 the cutter disk 32 and slice the cabbage. The slices will fall off through

the box 36 into a suitable receptacle placed underneath of the same.

If the knives or wings are to be sharpened 40 or replaced it will only be necessary to loosen the nuts and screws, with which they are secured to each other and to the spider 35, and if the width and distance between the curved edges of two adjoining wings are to be 45 varied, this can also be done by a suitable manipulation of these nuts and screws as will be readily understood.

I do not desire to limit myself to the details of construction herein shown and described, 50 but reserve to myself the right to vary, modify, and change the same within the scope of my invention.

What I claim and desire to secure by Letters Patent is—

55 In a slicer of the character described, a cutter disk, comprising a plurality of wings, beveled and curved cutting edges on said wings, the cutting edge of one wing in a different plane than the edge of the next adjoining wing, bands to connect the meeting edges of two adjoining wings at the periphery of said cutter, and means for securing said bands to said wings, a spider having a plurality of curved wings with beveled edges, 60 the inner ends of said first named wings adapted to be secured to the wings of said spider by rivets passed from above into said spider wings, substantially as described and for the purpose set forth.

70 In testimony whereof I have affixed my signature.

MIKE CHRZASTEK.
